(57) **CLAIM**

The ornamental design for a color-transfer wicking art kit as shown and described.

DESCRIPTION

FIG. 1 is a front perspective view of the color-transfer wicking art kit showing in broken lines a paper object that may be produced with the kit;

FIG. 2 is a front perspective view of the color-transfer wicking art kit of FIG. 1 omitting the paper object for clarity;

FIG. 3 is a front elevational view of the color-transfer wicking art kit of FIG. 2;

FIG. 4 is a rear elevational view of the color-transfer wicking art kit of FIG. 2;

FIG. 5 is a top view of the color-transfer wicking art kit of FIG. 2;

FIG. 6 is a left side view of the color-transfer wicking art kit of FIG. 2;

FIG. 7 is a right side view of the color-transfer wicking art kit of FIG. 2; and,

FIG. 8 is a bottom view of the color-transfer wicking art kit of FIG. 2.

The dashed lines in the figures illustrate unclaimed subject matter of the color transfer wicking art kit and form no part of the claimed design.

1 Claim, 8 Drawing Sheets
